(57) **CLAIM**

The ornamental design for a housing for electronic modules, as shown and described.

DESCRIPTION

The patent or application file contains at least one drawing executed in color. Copies of this patent or patent application publication with color drawing(s) will be provided by the Office upon request and payment of the necessary fee.

1. Housing for electronic modules

1.1 : Top

1.2 : Bottom

1.3 : Front

1.4 : Left

1.5 : Right

1.6 : Bottom view in perspective

1.7 : Top view in perspective
